ATTORNEYS

UNITED STATES PATENT OFFICE.

FREDERICK J. OSIUS, OF RACINE, WISCONSIN.

ELECTRIC CONNECTOR.

1,323,375.

Specification of Letters Patent.

Patented Dec. 2, 1919.

Application filed October 30, 1916. Serial No. 128,374.

To all whom it may concern:

Be it known that I, FREDERICK J. OSIUS, a citizen of the United States, and resident of Racine, in the county of Racine and State of Wisconsin, have invented new and useful Improvements in Electric Connectors, of which the following is a description, reference being had to the accompanying drawings, which are a part of this specification.

10 This invention relates to improvements in electrical connectors.

In separable and other connectors the electric terminals are usually provided with socketed portions in the form of binding 15 posts for receiving the ends of the wires to which it is connected and the wires are clamped in position by clamping screws threaded into the posts. This manner of construction is expensive to manufacture 20 and in use the binding screws tend to work loose and if clamped too tightly cut the wire.

It is one of the objects of the present invention to overcome the before mentioned 25 objectionable features and provide an electric connector in which the wires may be easily attached to the terminals of the connector without the liability of the wires accidentally becoming disconnected.

30 A further object of the invention is to provide an electric connector which is of simple construction, is strong and durable and is well adapted for the purpose described.

35 With the above and other objects in view the invention consists of the improved electric connector and its parts and combinations as set forth in the claims and all equivalents thereof.

40 In the accompanying drawing in which the same reference characters indicate the same parts in all of the views:

Figure 1 is a side view of the improved 45 electric connector shown connected to electric circuit wires, a part of the connector being shown in section;

Fig. 2 is a transverse sectional view taken on line 2-2 of Fig. 1;

Fig. 3 is a longitudinal sectional view 50 taken on line 3-3 of Fig. 2; and

Fig. 4 is a similar view taken on line 4-4 of the same figure.

Referring to the drawing the numeral 8 indicates the casing of the improved connector which is formed of an insulating material and is divided medially of its length

5 into two parts of which 9 is the plug portion and 10 the receptacle portion. Each half portion of the casing consists of an outwardly extending threaded end 11, a tubular cap 12 threaded thereon and a wire holding block 13 positioned within the cap and interposed between the cap and the threaded end of the casing.

The casing portions 9 and 10 are similar 65 to each other and the plug portion 9 is provided with projecting contact split spring pins 14 which telescopingly enter the bores of the tubular contact pins 15 mounted in the receptacle portion 10 of the casing. 70 These pins 14 and 15 of the respective casing portions also extend through said portions and project beyond the ends thereof and into openings 16 provided in the holding blocks 13. The openings 16 of each 75 block extend parallel to the axis thereof and diametrically opposite each other and communicate with the periphery of the blocks by slots 17 to provide for easily looping the end portions of the electric circuit wires 80 18 in the openings. The peripheral portions of the blocks are also provided with elongated locking slots 19 for receiving the bent over ends 18' of the wires 18.

The outer end portions of the pins 14 and 85 15 are of pointed or conical form as indicated by the numeral 14' and 15' to permit said ends to easily enter the opening 16 and to wedgily clamp the wires 18 in position and form an electrical connection therewith. 90

In connecting the half portions of the casing to the circuit wires the parts are disassembled and the wires are extended through the bore of the caps and then inserted laterally in the holding block openings and the wire ends are then bent over to form looped or hooked portions 20 and the end portions 18' thereof are then swung into the elongated locking slots 19. The holding blocks are then pulled into the caps 100 by the wires until they bear against the shoulders 21 of said caps and the caps are then threaded on their respective case portions. When the parts are thus assembled the looped or hooked portions of the wire 105 will be securely clamped between the holding blocks and the outer ends of the casing parts. The half parts of the casing are connected together as before described, by the entry of the split plug pins into the 110 bores of the recess pins.

From the foregoing description it will be

seen that the use of the binding posts in attaching wires to separable connectors is eliminated and that the wires are more firmly held and cannot be accidentally disconnected. It will further be seen that the connector is of very simple construction and is well adapted for the purpose described.

What I claim as my invention is:

1. An electrical connector, comprising a casing having a connector pin projecting therefrom, a cap mounted on the casing and having an end opening, a wire entering the cap opening and a holding block interposed between the casing and the cap and having an opening formed therein and into which opening the pin extends to form an electrical connection between the pin and the wire extending through both openings, said wire being clamped between the holding block and the cap.

2. An electrical connector, comprising a casing having a connector pin projecting therefrom, a cap mounted on the casing, a wire extending through the cap and a holding block interposed between the casing and the cap and having an opening and a recess formed therein and into which opening the pin extends to form an electrical connection between said pin and the wire which extends through the opening and is bent to enter the recess, said wire being clamped between the holding block and the cap.

3. An electrical connector, comprising a casing having a threaded portion and a projecting connector pin, a tubular removable cap threaded on the casing, and a holding member clamped between the casing and the cap and having an opening and a peripheral recess, said opening being in communication with the peripheral portion of the holding member to permit a wire to be inserted laterally therein and bent over one end of the member and the end of the wire to

be swung into the recess, the connector pin extending into the opening of the holding member to form an electrical connection with the wire.

4. An electrical connector, comprising a casing having projecting connector pins, a tubular removable cap threaded on the casing and extending around the pins, wires extending through the cap and a holding member interposed between the casing and the cap and having openings and recesses to permit the wires to be extended through the openings and the ends of the wires to enter the recesses, the connector pins extending into the openings of the holding member to clamp the wires therein and form electrical connections with the wires therein.

5. An electrical connector, comprising a two-part casing each part of which having connector pins extending therethrough and projecting outwardly therefrom, the inner end portions of the pins of one of said casing parts having a telescopic connection with the pins of the other casing part, caps removably mounted on the outer end portions of the casing parts, and holding members interposed between the caps and their respective casing parts, said holding members having openings extending therethrough which are in communication with the peripheral portions of the members and which receive the connector pins, said holding members also having peripheral recesses, the connector pins electrically engaging wires which extend through the openings of the holding members, said wires also extending between the holding members and the casing parts and entering the peripheral recesses.

In testimony whereof, I affix my signature.

FREDÉRICK J. OSIUS.
